THREAD CUTTER FOR AUTOMATIC LOOMS

Ernest P. Guerin, Lawrence, Mass., assignor to
 Crompton & Knowles Loom Works, Worcester,
 Mass., a corporation of Massachusetts

Application April 21, 1941, Serial No. 389,576

7 Claims. (Cl. 139—303)

This invention relates to thread cutters for automatic looms and it is the general object of the invention to provide a cutter for severing the thread of the outgoing bobbin without cutting the thread extending from the adjacent selvage to a shuttle boxed under the magazine.

In weft replenishing mechanisms more particularly of the pick and pick type it is customary to replenish one shuttle while another shuttle is located on the same side of the loom as the replenishing mechanism. The thread of the outgoing bobbin must be severed to prevent it from being drawn into the shed by the active shuttle, but the thread leading from the selvage to the other shuttle must remain intact so that when called into action said other shuttle can weave properly. Weft replenishing mechanisms are ordinarily provided with a clamp which holds the thread of the outgoing bobbin in forward position after transfer while the thread to the other bobbin moves backwardly with the lay in a direction away from the thread held by the clamp. It is an important object of my present invention to provide a thread cutter operated by backward motion of the lay and having a zone of operation which lies behind the thread of the outgoing bobbin but in front of the thread extending to the boxed shuttle.

It is a further object of my present invention to provide a thread cutter normally in forward position but movable toward cutting position along a path having two components the first of which is rearward against the thread to be cut to bend it and the second of which is upward so that the bent thread can snap forwardly to a position in front of the cutter as the latter returns to forward position. These motions of the cutter occur when the lay is in rearward position and the downward motion occurs shortly after the lay starts forwardly, hence the cutter descends in front of the thread extending to the boxed shuttle and remains in front of that thread during continued advance of the lay.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a front elevation of part of a loom having my invention applied thereto,

Fig. 2 is a plan view taken in the direction of arrow 2, Fig. 1, with the lay in rearward position,

Fig. 3 is an end elevation on an enlarged scale looking in the direction of arrow 3, Fig. 2,

Fig. 4 is an enlarged vertical section on line 4—4, Fig. 2 looking in the direction opposite to that in which Fig. 3 is taken and showing the cutter at the completion of its opening stroke preparatory to a cutting operation.

Fig. 5 is a view similar to Fig. 4 but showing the parts restored to normal position such as that existing when the lay approaches front position.

Fig. 6 is a rear elevation looking in the direction of arrow 6, Fig. 3, and

Fig. 7 is a diagrammatic view similar to a portion of Fig. 2 showing a bend produced in the clamped thread of the outgoing bobbin by the cutter blade.

Referring to the drawings, the loom frame 10 includes a breast beam 11 over which the fabric F passes. The lay L is provided with a reed R through which the warp threads W extend. Mounted on the breast beam is a temple T having a rearwardly extending shank 12 with the usual burr pod 13. The lay is provided with a protector rod 14 of usual construction for a purpose to appear hereinafter.

The right end of the lay is provided with a gang G of shuttle boxes including top and bottom cells 15 and 16, respectively, each having a binder 17 which assists in holding shuttles in the cells. The upper and lower cells in the present instance are provided with shuttles S' and S2, respectively, and the boxes rise and fall with respect to the lay by means of mechanism not shown but operating through a box lifter rod 18. As shown in Fig. 1 the lower cell 16 with its shuttle S2 is in active position opposite the shuttle race 20, but it is to be understood that the boxes are shiftable downwardly so that the other shuttle S' can also become active.

The shuttle boxes are preferably controlled to call a plurality of shuttles into action in a definite order or rotation so that three successive picks will be laid by three different shuttles for the purpose of mixing filling. Certain features of my invention however are not limited to automatic looms of this particular type. When operating as preferred, however, the shuttle box gang G will be up for two picks and then down for two picks, the boxes thereby having a cycle which is completed in four picks of the loom. When the boxes are down with a shuttle in the top cell, the shuttle will be picked to the left hand side of the loom on the first pick of the repeat and on the second pick an-

other shuttle arriving from the opposite side of the loom will enter the top cell. The gang G then rises and a shuttle previously stored in the lower cell is picked to the left side during the third pick, and during the fourth pick another shuttle arriving from the left hand side will enter the lower cell. The boxes will then drop to start the next cycle, and if replenishment has occurred in the top cell while the latter is raised as set forth in my co-pending application Serial No. 365,093, there will be a thread 25 extending from the thread cutter designated generally at C to the adjacent selvage of the fabric, and there will be also a second thread 26 extending from the selvage to the shuttle in the lower box cell 16 which is now inactive.

The thread cutter C of itself forms no part of my present invention and may be of any approved form, such for instance as that shown in my previously mentioned application or in Patent No. 1,610,562. The thread cutter ordinarily moves to the forward position indicated in Fig. 1 after a replenishing operation so that thread 25 will ordinarily extend to the right and forwardly from the fell of the cloth regardless of the position of the lay. The lay moves rearwardly immediately after replenishment to cause the thread 26 to be inclined to the right and rearwardly from the fell of the fabric. As shown in Fig. 2 there will be a considerable angle between the threads 25 and 26 when the lay is on back center position.

The magazine for effecting replenishment is not set forth herein and it is thought sufficient for present purposes to state that the cutting by the cutter C is effected at the time of replenishment and cutter C not only cuts but also clamps the thread 25. It is necessary to cut thread 25 adjacent to the selvage prior to the next replenishing operation of the loom to prevent this thread from being drawn into the shed and thus causing a thick place in the fabric.

In carrying my present invention into effect I form the temple with a head 30 the rear side of which is provided with the customary spaced vertical cutter blades 31. Mounted for sliding motion in a vertical slot 32 in the head is a cutter carrier 35 the rear end of which supports a downwardly extending blade 37 which may be shaped as shown in Fig. 4, for instance, with a rounded lower rear edge 38. The carrier is provided with a slot 39 into which projects a guide stud 40 threaded into the head 30. A stud 41 projecting laterally from the head has secured thereto one end of a coil spring 42, the other end of which extends downwardly as at 43 to be wrapped around a stud 44 on the carrier 35. The effect of spring 42 is to move the carrier and cutter blade rearwardly, but this effect is normally nullified by a stronger spring 45 wrapped around a stud 46 supported by the head 30 and having a depending arm 47 which passes behind a stud 48 secured to the carrier 35. The stud 48 is below the stud 44, while the springs and their studs may be located substantially as shown in Figs. 4 and 5.

The lower end of arm 47 may be provided with an eye 50 which receives leather thong 51 the rear end of which passes around the protector rod 14. In the present instance I use the protector rod for convenience and it is to be understood that I am not necessarily limited to this rod as a means for anchoring the rear end of the thong.

Under normal conditions when the lay is in the forward part of its stroke the arm 47 presses on

the stud 48 to move the carrier 35 forwardly against the action of spring 42. Under these conditions the force of spring 42 is exerted through stud 44 above the stud 48 and the cutter blade 37 and its carrier are thereby held in low position.

As the lay moves rearwardly the thong is straightened and arm 47 starts to move to the right from the position shown in Fig. 5 toward the position shown in Fig. 4, thus permitting spring 42 to move the slide rearwardly. As long as both springs exert their forces on the carrier the latter will move rearwardly in a substantially horizontal line, but as the lay continues its rearward motion arm 47 will move backwardly away from stud 48, thus leaving the spring 42 in control of the carrier 35. During backward horizontal motion of the carrier, surface 38 of blade 37 engages thread 25 to produce a bend 52 in it, as indicated in Fig. 7.

20 The carrier 35 has a forward horn 55 provided with a rear normally vertical surface 54 which engages the downwardly and rearwardly inclined edge 56 of the head 30 during backward motion of the lay, thereby preventing further substantial backward motion of the carrier 35, and it is for this reason that the arm 47 moves rearwardly away from the stud 48 as the lay approaches its back center position. The head 30 is provided with a downwardly and forwardly inclined surface 57, while the carrier 35 has a normally horizontal surface 58 extending rearwardly from the horn 55 and under surface 52 for engagement with the latter. Since stud 44 is below the horn 55 the latter tends to turn so that the surface 54 33 will be aligned with the surface 56 on the head. This turning of the carrier can occur because of the normal relation of surfaces 57 and 58, and also because of the sliding pivot provided by slot 40 and pivot screw 41. As the carrier turns angularly to align surfaces 57 and 58, the blade 37 rises to a position above and to the rear of thread 25, reaching its highest position when the lay is on back center. During upward motion of blade 37 it rises to a point above thread 25 and the latter snaps back to the position of Fig. 2 in front of blade 37.

45 As the lay starts to move forwardly the arm 47 moves forwardly toward the position of Fig. 5, ultimately engaging stud 48 the first effect of which is to rock the carrier 35 in a clockwise direction as viewed in Fig. 4 to lower the blade 37 behind the thread 25, after which continued forward motion of arm 47 as the lay advances causes horizontal forward motion of the carrier against the action of spring 42 until the blade 37 cooperates with the blades 31 to cut the thread 25. The thong 51 will become slackened during forward motion of the lay after forward motion of the carrier 30 is arrested by engagement of pivot screw 40 with the rear end of slot 39.

It will be noted from Fig. 2 that the downward motion of the blade 37 as the lay starts forwardly from its rearward position occurs when thread 26 is behind the zone of operation of the cutter, and the spring arm 47 acts to move the carrier 35 and the cutter blade forwardly in front of thread 26 as the latter approaches thread 25 with the advancing lay. The cutter is therefore always kept in a position well in advance of thread 26 and the latter is in no danger of being cut.

From the foregoing it will be seen that I have provided a simple thread cutter which is set for operation by backward motion of the lay and has its severing action during the first part of the forward motion of the lay when the thread 26 is

out of the range of action of the cutter. It will further be seen that the cutter blade 37 descends along a path behind the thread 25 which it is to cut but in front of the thread 26 which must remain intact. It will also be seen that the thread cutter has a compound motion the first part of which is rearward and substantially horizontal to bend thread 25 at 52, and the second part of which is upward to open the cutter for action and permit the thread 25 to snap forwardly to a position in front of cutter blade 37. On the actual cutting stroke the cutter traverses its opening path in reverse order and moves downwardly to a position behind thread 25 and then forwardly, being in front of thread 26 at all times.

Having thus described my invention it will be seen that changes and modifications may be made therein by those skilled in the art without departing from the spirit and scope of the invention and I do not wish to be limited to the details herein disclosed, but what I claim is:

1. In a thread cutter for a loom having a lay reciprocating between front and back center positions and provided with a thread extending from a thread clamp to the adjacent selvage, a normally stationary support mounted in front of the lay having cutter means mounted thereon, a cutter mounted for backward and forward motion on the support, two opposed springs one of which is stronger than the other and tends normally to hold the cutter in forward closed position relatively to the cutter means and the other of which tends to move the cutter to rearward open position relatively to the cutter means, a stop to limit rearward motion of the cutter, and connections between the stronger spring and the lay to overpower the stronger spring during backward motion of the lay, whereupon the weaker spring moves the cutter to rearward open position when the lay is in rearward position and behind said thread, said stronger spring thereafter operative during forward motion of the lay to overpower the weaker spring and move the cutter to forward closed position relatively to the cutter means to cut the thread.

2. In a thread cutter for a loom having a lay reciprocating between front and back center positions and provided with a thread extending from a thread clamp to the adjacent selvage and having a second thread extending from a shuttle on the lay and extending to the selvage behind the first thread, a normally stationary support mounted in front of the lay having cutter means mounted thereon, a cutter movably mounted on the support, relatively strong spring means to hold the cutter in forward closed position relatively to the cutter means, relatively weak spring means tending to move the cutter to rearward open position relatively to the cutter means and normally overpowered by the relatively strong spring means, a stop for the cutter to limit rearward motion of the latter, and means connecting the lay to the relatively strong means to move the latter rearwardly during the backward stroke of the lay, whereupon the relatively weak spring means moves the cutter to rearward open position against said stop behind the first thread and in front of the second thread, the relatively strong spring means moving the cutter forwardly when the lay moves forwardly from the rearmost position thereof and overpowering the relatively weak spring means to return the cutter to normal closed forward position to cut the thread.

3. In a thread cutter for a loom having a lay

reciprocating between front and back center positions and provided with a thread extending from a thread clamp to the adjacent selvage, a normally stationary support mounted in front of the lay having cutter means mounted thereon, a cutter mounted on the support, means defining a sliding and rocking connection between the cutter and the support limiting rearward motion of the cutter, two springs connected to the support and both acting on the cutter, one of said springs being stronger than the other and acting to hold the cutter in forward closed position relatively to the cutter means and the other spring tending to move the cutter rearwardly toward said stop and to open position relatively to the cutter means, and connections between the lay and the stronger spring effective during rearward motion of the lay to move the stronger spring rearwardly, whereupon the other spring moves the cutter with a combined backward and upward rocking motion relatively to the support to place the cutter behind the thread when the lay is in rear position, the stronger spring operative during the following forward motion of the lay to move the cutter forwardly against the action of said other spring by a combined downward rocking and forwardly sliding motion relatively to the support from a point behind said first thread to closed position relatively to the cutter means to cut said thread.

4. In a thread cutter for a loom having a lay reciprocating between front and back center positions and provided with a thread extending from a thread clamp to the adjacent selvage, a normally stationary support mounted in front of the lay having cutter means mounted thereon, a cutter mounted on the support and having a substantially horizontal slot therein, guide and stop means on the support entering the slot and constituting with the latter a sliding and rocking connection between the cutter and the support, a relatively strong spring connected to the cutter to move the latter forwardly with respect to the support, a weaker spring connected to the cutter and tending to move the latter rearwardly, and connections between the lay and the stronger spring to overpower the latter as the lay moves rearwardly, whereupon the weaker spring causes the cutter to move rearwardly by a relative motion between the slot and said guide and stop means followed by an upward pivotal motion of the cutter with respect to the support caused by engagement of the guide and stop means with the forward end of the slot in said cutter to open the latter in a position behind the first named thread, the stronger spring acting during the following forward motion of the lay to move the cutter pivotally with respect to the support in a downward direction behind said thread and thereafter move the cutter with a substantially horizontal forward sliding motion relatively to the support to move the cutter to closed position relatively to the cutter means to cut said thread.

5. In a thread cutter for looms having a lay reciprocating between front and back center positions and provided with a thread extending from a thread clamp to the adjacent selvage, a normally stationary support mounted in front of the lay, cutter means mounted on the support, a second cutter mounted on the support for movement relative thereto, two opposed springs one of which is stronger than the other and tends normally to hold the second cutter in forward closed position relatively to the first cutting means, the other of said springs tending to move

the second cutter to rearward open position relative to the first cutter means, connections between the stronger spring and the lay to overpower said stronger spring during backward motion of the lay, whereupon the weaker spring moves the second cutter rearwardly, guide means for the second cutter to cause said weaker spring to move the second cutter rearwardly in a substantially horizontal direction against the thread to bend the latter and thereafter cause said weaker spring to raise the second cutter to a point above and rearwardly of and out of engagement with the thread, said stronger spring thereafter operative during forward motion of the lay to overpower the weaker spring and cooperate with the guide means to move the second cutter downwardly to a position behind the thread and then forwardly to closed position relatively to the first cutter means to cut said thread.

6. In a thread cutter for a loom having a lay reciprocating between front and back center positions and provided with a thread extending from a thread clamp to the adjacent selvage, a normally stationary support mounted in front of the lay, cutter means mounted on the support, a second cutter mounted on the support for movement relatively thereto, means defining a sliding and rocking connection between the second cutter and the support and limiting rearward motion of the second cutter relatively to the support, two springs connected to the support acting in opposite directions on the second cutter, one of said springs being stronger than the other spring and acting to hold the second cutter in forward closed position relatively to the first cutter means, the other spring tending to move the second cutter rearwardly and cooperate with said means to move the second cutter to open position relatively to the first cutter means, and connections between the lay and the stronger spring effective during rearward motion of the lay to move the stronger spring rearwardly out of controlling position relatively to the second cutter, whereupon said other spring cooperates with the sliding and rocking connection to move the second cutter rearwardly in a

substantially horizontal direction by reason of the sliding feature of said connection to a position against the thread to bend the latter rearwardly and then rock said second cutter upwardly by 5 reason of the rocking feature of said connection to a position above and to the rear of and out of engagement with said thread when the lay is in rearward position, the stronger spring operative during the following forward motion of 10 the lay to cooperate with the rocking feature of said connection to move the second cutter downwardly against the action of said other spring to a position behind the thread and then forwardly in cooperation with the sliding feature 15 of said connection to closed position relatively to the first cutter means to cut the thread as the lay moves forwardly.

7. In a thread cutter having a lay reciprocating between front and back center positions 20 and provided with a thread extending from the thread clamp to the adjacent selvage, substantially fixed cutter means, a cutter blade movable rearwardly from a closed cutting position relatively to the fixed cutting means, controller means 25 for the cutter blade including two members acting to move the cutter blade in opposite directions, one of said members being stronger than the other and connected to the lay to be overpowered thereby during backward motion of the 30 lay, said controller means also including a support for the cutter blade with respect to which the latter can have horizontal and upward motions, the weaker member cooperating with the support to move the cutter blade rearwardly 35 against the thread to bend the latter rearwardly and then raise the cutter blade to a position above and behind the thread out of contact with the latter as the lay moves rearwardly, whereupon the thread snaps back to its original position in front 40 of the cutter blade, the stronger member thereafter cooperating with the support to move the cutter blade downwardly to a position behind the thread and then forwardly to closed position relatively to the cutter means as the lay advances.

45 ERNEST P. GUERIN.
